UNITED STATES PATENT OFFICE.

MAX MULLER, OF NEW YORK, N. Y.

DESIGN FOR A HAIR FRINGE.

59,261.

Specification for Design.

Patented Oct. 4, 1921.

Application filed October 4, 1919. Serial No. 328,594. Term of patent 7 years.

To all whom it may concern:

Be it known that I, MAX MULLER, a citizen of the United States, and a resident of the city of New York, borough of Manhattan, in the county and State of New York, have invented a new, original, and ornamental Design for a Hair Fringe, of which the following is a specification, reference being had to the accompanying drawing, forming a part thereof.

The figure is a perspective view of the hair fringe showing my new design.

I claim:

The ornamental design for a hair fringe as shown.

MAX MULLER.
